(57) **CLAIM**

The ornamental design for a display screen with graphical user interface, as shown and described.

DESCRIPTION

The file of this patent contains at least one photograph executed in color. Copies of this patent with color photograph(s) will be provided by the Office upon request and payment of the necessary fee.

FIGURE is a front view of a display screen with graphical user interface, showing our new design.

The broken line rectangle showing the display screen illustrates portions of the display screen with graphical user interface that form no part of the claimed design.
